UNITED STATES PATENT OFFICE.

ADOLPHE CLÉMENT-BAYARD, OF LEVALLOIS-PERRET, FRANCE.

DIRIGIBLE OF THE RIGID TYPE.

1,265,302.

Specification of Letters Patent.

Patented May 7, 1918.

Application filed August 14, 1914. Serial No. 856,814.

To all whom it may concern:

Be it known that I, ADOLPHE CLÉMENT-BAYARD, a citizen of the Republic of France, residing in Levallois-Perret, Seine, France, 5 have invented certain new and useful Improvements in Dirigibles of the Rigid Type, of which the following is a specification.

The present invention has for its object a dirigible of the rigid type, the girder of 10 which is constituted in such a manner that it will withstand the strains due to its own weight when it rests upon two supports conveniently located at two points in its length. In combination with these conditions, it also 15 relates to the employment of special devices for the deflation of the gas balloonets; means for rapidly removing the outer envelop from the girder; of laterally guying the girder throughout its entire length, and if 20 necessary for preserving one or two inflated balloonets to contribute to maintaining the girder in its normal vertical position. The whole thus constituted has been established and combined in such a manner that it is 25 possible in case a storm should break when the airship is resting unprotected on the ground, to protect it from the effect of wind capable of breaking it or of tearing it from its moorings.

30 Figure 1 is a side elevation of my improved girder;

Fig. 2 is a cross-section thereof;

Fig. 3 is a plan-view of the communication passage;

35 Figs. 4 and 5 are detailed views of shock absorbers interposed between the car and the girder;

Fig. 6 is a detailed view of a shock absorber interposed between the car and the 40 ground;

Figs. 7 and 8 represent a tearing bar in side and front elevation respectively;

Figs. 9 and 10 are elevational and plan 45 views respectively of portions of a dirigible, and details of tearing mechanism operable from the platform;

Figs. 11 and 12 are views showing a cross-section and an elevation of a portion of a dirigible and details of the tearing mechanism operable from the ground;

Fig. 13 is a diagrammatic view showing another form of tearing mechanism;

Fig. 14 is a diagram of a form of tearing lacing;

50 Figs. 15 and 16 are cross-sectional and ele-

vational details respectively of drums for winding and unwinding the blinds; and

Figs. 17 and 18 are cross-sectional and elevational views respectively of deflating mechanism for the balloonets.

When a girder rests upon two supports, strains are produced in its various elements (uprights, diagonals, upper framework and lower framework); these are either compression or tension strains and their value 60 is well determined. The girder generally comprises elements whose constitution cannot be determined solely by the conditions of resistance; certain conditions necessitated by its employment should also be considered. It will be understood that it may comprise elements which, owing to the dimensions of their section, would be particularly suitable for withstanding compression strains and that consequently it would be 65 desirable, with a view to the minimum weight of the whole, to concentrate the said compression strains upon these elements; in this case the tension strains are reserved for the elements of reduced cross-section.

70 This is the case with the girder for rigid dirigibles forming the object of the present invention, and which is represented in side elevation in Fig. 1 and in cross-section in Fig. 2. This girder is constituted in the following manner:

The lower framework by the communication passage *a* extending throughout its entire length and represented in plan in Fig. 3.

75 The upper framework by light beams *b*.

The uprights by vertical pylons *c* located in the median plane.

The diagonals by wires or cables *d* and finally, the transverse rings located in the 80 plane of the uprights by framework members, preferably tubes *e*, connected together and braced by a triangle system of wires *f*, the wires being under tension and assuring the non-deformation of the external 85 contour of the rings. The balloonets are located between these rings and the outer envelop preferably incases the balloonets and the framework of the girder, including the elements constituting the rings.

90 When it is desired that a girder complying with this description and whose balloonets are deflated should be able to rest upon any unlevelled piece of ground upon which it might only be supported at two 95 100

105 110

points, practically speaking, considerable strains arise. The present invention consists in particular in assigning as positions for the two points of support, places which 5 will localize the compression strains in the lower frame-work or communication passage.

In order to attain this result the following arrangements, which are given by way of 10 example, may be adopted:

Two cars *h* containing the motor mechanisms are utilized for the points of support. These cars are of course designed to withstand particular strains; they are provided with an appropriate supporting surface at the upper part upon which the girder rests. 15

The girder should be capable of withstanding strains due to its own weight, to 20 the weight of the envelops of the balloonets, to the weight of the fuel and of the ballast before it is discharged, to the weight of the outer envelop, if, after it has been torn, it remains folded or rolled, to the weight of 25 the empennage and of the rudders mounted at the rear, to the weight of the navigation and observation cabin located at the front extremity of the passage.

As will be understood, it is possible to arrange the supporting cars in such a manner 30 that the upper framework is exposed to tension strains only, the lower framework or passageway supporting the compression strains. This is an essential feature of the 35 present invention and, to use mechanical terms, it may be said that the moments of flexure from one end of the girder to the other would then have the same sign, of course with two maxima, plumb with the 40 supports: it would also be possible to satisfy another condition, that of the minimum of strain and of weight.

Given these conditions, if on landing it be 45 desired to protect the airship from a threatened storm, the following method is adopted:

The pneumatic shock absorbers or other landing devices *i* are put out of action so 50 that the cars rest directly upon the ground. The pneumatic shock absorbers are constructed in some suitable manner, three forms being indicated in section in Figs. 4, 5 and 6: Figs. 4 and 5 relate to two constructional forms of shock absorber *j* (Fig. 1) interposed between the car and the girder 55 and Fig. 6 relates to a form of the shock absorbers *i* interposed between the car and the ground.

In the arrangement illustrated in Fig. 4, 60 the absorber is constituted by a pneumatic ring *r* interposed between the bottom of the girder and the car and traversed by a rod *s* integral with the girder; this rod serves to eliminate the action of the shock absorber in the condition of repose, by bringing into 65 contact with it the threaded rod integral

with the car, in causing it to rotate by means of the handwheel *u* until the lower end of the rod *s* bears against the top of the said threaded rod.

In the modification illustrated in Fig. 5 a 70 pneumatic ball *r'* is interposed between the girder and the car; in acting by means of the hand wheel *u'* which is screwed onto the threaded rod *t'* the fork *x* is caused to rise and fall in order to bring it into contact with the two rods *s'* fixed beneath the 75 girder.

In the arrangement illustrated in Fig. 6 which relates to the shock absorber arranged at the bottom of the car, the pneumatic 80 cushion *r''* is surrounded by a frame *y* which is lowered by means of oppositely threaded screws *a'* to bring it into contact with the ground in such a manner that by rotating the screws *a'* the pneumatic cushion may be 85 relieved of the weight of the girder, while the airship is at rest.

By means of these devices, the shock absorbers *j* interposed between the beam and the cars are put out of action and the girder 90 can be caused to bear directly upon the appropriate points of the support. Guying such as shown in Fig. 2 is then effected by means of cables *k* fixed on either side of the girder and anchored to piles driven into the 95 ground.

The girder can then, if desired, be freed from its outer envelop. With this object in view the envelop is provided with tearing devices ready for use. These devices may 100 be analogous to the well known tearing bar of spherical balloons and are represented in Figs. 7 and 8, arranged along the top and sides of the cylinder. Cords *a''* and *b''* attached in advance and adapted to be operated from the top of the dirigible and from the ground respectively, effect this tearing as indicated in Figs. 9, 10, 11 and 12. Funnels provided with stairways *c''* afford access to the top side for actuating the cords *a''*. 110 When the panels of fabric have been released, the cords fixed to the upper generatrix of each half panel are pulled for the purpose of bringing the fabric to the ground and turning it over. It will of course be 115 understood that the tearing devices above referred to may be replaced by other devices, such for example as that represented in Fig. 13 which consists of passing a lace *l* alternately through eyelets *m* provided on the 120 edges of the adjacent panels; this lace can be withdrawn by exerting pulling upon one of its ends. Another method consists of laces *n* sliding in loops *o* (Fig. 14).

Instead of bringing the half panels to the 125 ground, drums *p* and *q*, represented in Figs. 15 and 16, may be employed in the manner adopted for certain kinds of blinds; these drums permit of winding or unwinding and in the latter case the outer envelop remains 130

upon the girder when rolled or folded as diagrammatically represented in Figs. 15 and 16.

Finally, the balloonets are deflated in some suitable manner, for instance by means of a tearing bar *v* as shown in Figs. 17 and 18. One or two of these balloonets may remain inflated to assist in maintaining the girder in the normal vertical position if this is necessary, and compatible with the velocity of the wind.

The dirigible thus prepared is able to resist the effects of the storm under better conditions than if it were allowed to remain in its normal state; the material will be preserved and the dirigible can again ascend when atmospheric conditions have enabled it to be reinflated either covered by its outer envelop or without it if necessary.

20 Claims:

1. In a dirigible of the rigid type, the combination with a longitudinally disposed framework comprising vertical pylons, diagonally disposed wires, rings disposed transversely of the framework, balloonets located between said rings, an envelop covering the balloonets and rings, means for deflating the balloonets, and a tearing device for the envelop.

2. In a dirigible of the rigid type, the combination with a longitudinally disposed framework comprising vertical pylons, diagonally disposed wires, rings disposed transversely of the framework, balloonets disposed between said rings, tearing devices for the balloonets, an envelop covering the balloonets, and tearing means for the said envelop.

3. In a dirigible of the rigid type, the

combination of a longitudinally disposed framework comprising vertical pylons, diagonally disposed wires, rings disposed transversely of the framework, balloonets disposed between such rings and each having an individual envelop, individual deflating means for the balloonets, an envelop covering the rings and balloonets, and a tearing and stripping device for the said envelop located in position for external operation.

4. In a dirigible of the rigid type, the combination of a longitudinally disposed girder having an upper and a lower member, the lower member being relatively heavy and adapted to resist compression strains, and the upper member being relatively light and adapted to resist tension strains, and two supports disposed beneath the lower member and adapted to rest upon the ground.

5. A dirigible of the rigid type, comprising a girder having a lower compression member and an upper tension member, uprights between these members, rings formed transversely of the girder and composed of framework members and a triangular system of bracing wires, the lower member being provided with two separated supports, balloonets located between the said rings, individual deflating means for the balloonets, an envelop incasing the balloonets, and tearing and stripping means for the said envelop.

In witness whereof I have hereunto signed my name in the presence of two subscribing witnesses.
